FLAP LOCKING SHIPPING BOX

Charles H. Goodyear, Portland, Oreg., assignor of
one-half to Frank C. Stettler, Portland, Oreg.

Application March 26, 1934, Serial No. 717,314

2 Claims. (Cl. 229—45)

The object of my invention is to provide an inexpensive light weight box adapted especially for permitting easy inspection of its contents, as is required for example in the shipping of fruit. When fruit is shipped there is generally an inspection of the fruit at the shipping point by a Federal or State government agent, with subsequent inspection by the commission merchant after the fruit has reached its destination, and finally inspection from time to time by prospective purchasers. It is essential, therefore, that a box intended for the use mentioned be so constructed that it may not only be easily opened to allow inspection of its contents, but also be repeatedly opened and closed and its cover or closure element securely fastened after each inspection.

The particular object of my invention, accordingly, is to provide a box with a hinged cover or closure section with a simple means for keeping the cover securely closed, but also facilitating the releasing and opening up of the cover by hand whenever it is desired to do so.

I attain this object by providing a hinged cover section terminating in a lip, the exterior face of which lip at its free edge is provided with a locking abutment, and by providing a cooperating locking abutment on the interior face of the box wall facing the locking lip, so that when the cover section is pressed down into closed position the cooperating locking abutments will engage each other; and further, in order to maintain such locking engagement, by making the cover lip adapted normally to be resiliently held at an obtuse angle with the interior face of the cover section, so that when the cover is closed the locking abutment of the cover lip will be held under tension against the opposed side wall, thus assuring the engagement of said cooperating locking abutments until the cover is manually released.

A further object of my invention—and the preferred mode of constructing my box—is to provide a hinged cover or closure section of the construction mentioned, for both top and bottom of the box so that the box may be readily opened without turning it over—which in a heavy box is an awkward procedure—and further to permit and facilitate the inspection of the pack at both top and bottom.

A further object of my invention is to provide a box embodying the special features above mentioned but constructed in such manner that it may be folded flat for shipment.

55 The above mentioned objects and incidental

features I attain by construction of my box in the manner illustrated in the accompanying drawings and hereinafter fully described.

In the drawings:

Fig. 1 shows a perspective of my pasteboard box closed with the upper hinged cover section sealed by a strip of gummed paper;

Fig. 2 illustrates the mode in which the hinged top or cover section of the box is manually released and opened;

Fig. 3 shows a perspective section taken transversely thru the middle of my box in the position shown by Figs. 1 and 2, and illustrates the details of construction of my box;

Fig. 3a is an enlarged sectional detail of the front lower corner of Fig. 3;

Fig. 4 is a fragmentary perspective section of a corner of my box giving a view of the interior face of the side wall with which the cover section is interlocked when closed;

Fig. 5 shows a blank sheet cut for making my box;

Fig. 6 shows the body of the box formed and the box arranged flat for shipment;

Fig. 7 shows an insert or lining to be placed within the box after the box has been set up to receive the pack, which lining serves to strengthen the box; and

Fig. 8 shows a strip which may be placed inside on the bottom of the box, also placed on top of the pack to add strength to the box and to give greater protection to the pack.

Referring first to the blank shown by Fig. 5, the broken lines represent folds or creases in the paper board or material from which the box is made. The rectangles *a* and *b* constitute the two cover sections, *a* denoting the upper cover or lid, as illustrated in Figs. 1, 2 and 3. Both cover sections are provided with lips *c*, *c'* which are folded up on the lines *d*—*e* and *d'*—*e'*, respectively, and the flaps *f* and *f'* of the lips *c* and *c'* are folded back on the lines *g*—*h* and *g'*—*h'* and securely fastened against the outer face of the lips by wire staples, or other means, to form a locking abutment, as shown in Fig. 3.

The rectangle *i* in Fig. 5 constitutes the right front wall or front face of the box as viewed in Figs. 1, 2 and 3, and the flaps *j* and *j'* folded upon the lines *k* and *k'*, respectively, are fastened against the inside of the face *i* (see Fig. 4) to form the cooperating locking abutments to engage the abutments *f* and *f'*, respectively, of the lips *c*, *c'* of the top and bottom cover sections. *o* and *n* are the ends of the box, and *m* is the rear side wall or face.

I prefer to make my box of light, semi-resilient material, such as paper board, with the lip of each cover section normally making an obtuse angle with the inside face of the cover so as to 5 keep the locking abutment of the lip pressing against the adjacent wall of the box when the cover is closed, thus securely locking the cover in place.

When the box has been set up ready for use 10 the lining or insert *l* shown in Fig. 7 is placed inside the box with the surface *i'* covering the interior face of the front side wall *i* of the box, and the surfaces *o'*, *n'* covering the inside of the ends *o* and *n*, respectively, and the sections *m'* 15 covering the inside of the rear wall *m*. When the bottom cover has been closed by pressing the lip *c'* up between the front wall *i* and section *i'* of the lining, causing the abutment *f'* to engage the abutment *j'*, the board or lining strip *b'*, shown 20 in Fig. 8, is placed inside the box on the bottom and serves as a supporting brace for the sides and ends of the insert *l*. The box may then be filled and a strip similar to *b'* placed on top of the box contents. Finally the top cover is closed 25 by pressing the lip *c* down between the front wall *i'* of the box and the corresponding section of the lining *i'* until the locking abutment *f* engages the locking abutment *j*. The resiliency of the material of which the box is made, which 30 causes the lip *c* normally to extend at an obtuse angle with the under face of the cover *a* (see Fig. 3) will keep the abutment *f* pressed firmly against the interior face of the front wall *i* and thus engaged with the abutment *j*. This is also 35 true of the lip *c'* and abutment *f'* of the lower cover or closure section. Furthermore, the pressure of the box contents against the lining *i'* will serve as an additional means of keeping the lips and abutments of the upper and lower covers 40 firmly in locking engagement.

The opening up of either cover is a simple matter and is done easily by inserting the hand between the cover lip or closure section, and outside wall, as shown in Fig. 2, forcing the outside wall *i* away sufficiently from the cover lip to disengage the locking abutments and permit the cover or closure section to be pulled up. Should it be desired to seal the box to protect it against unauthorized opening, or for other reasons, this 45 can be done by a gummed strip of paper or seal, as indicated at *s* in Fig. 1.

I claim:

1. A box including a body, a cover movably connected to the body, one wall of the body being composed of two sections forming a double thickness and open at the upper edge, the cover having a locking lip to be inserted between the sections of the wall of double thickness, the free edge of the locking lip being provided on the outer surface thereof with a locking abutment, the free upper edge of the outer section of the wall of double thickness being provided on the inner surface thereof with a strip forming a locking abutment, the locking lip being inserted between the sections of the wall of double thickness to cause the locking abutment on the lip to ride past below and beneath the locking lip on the outer section of the wall of double thickness, whereby to lock the cover to the body, the locking means being wholly concealed when the cover is in closing position and the abutments being separable to release the cover by outward pressure on the abutment-carrying section of the wall of double thickness, whereby the locking function of the box is capable of continued reuse. 15 20 25

2. A box including a body and a cover therefor movably secured at one edge to the body, one wall of the body being composed of two sections forming a double thickness, with the upper portion of the outer section of such wall being turned inwardly and downwardly against the inner surface of such section to provide a locking abutment between the sections, the cover having a locking lip to be inserted between the sections of the double wall of the body in closing the cover, said locking lip having its lower edge turned upwardly 30 and against the outer surface of the lip to provide a locking abutment on said outer surface, the lip of the cover being inserted between the sections of the double wall to cause the abutment on the lip to ride past the abutment on the double wall section and beneath the same to lock the lip and thereby the cover in place, the locking means provided by the abutments being wholly concealed when the cover is in place and being separable to release the cover at will by spreading the outer section of the double wall to a degree to permit the abutment on the locking lip to move freely upwardly past the abutment on the outer section of the double wall, whereby the locking function of the box is capable of continued reuse. 35 40 45 50

CHARLES H. GOODYEAR.
